UNITED STATES PATENT OFFICE

121,872

DESIGN FOR A GRINDING MACHINE

Milburn A. Hollengreen and Harold E. Balsiger,
Waynesboro, Pa., assignors to Landis Tool Com-
pany, Waynesboro, Pa.

Application June 6, 1940, Serial No. 92,864

Term of patent 14 years

To all whom it may concern:

Be it known that we, Milburn A. Hollengreen and Harold E. Balsiger, citizens of the United States of America, residing at Waynesboro, in the county of Franklin and State of Pennsylvania, have invented a new, original, and ornamental Design for a Grinding Machine, of which the following is a specification, reference being had to the accompanying drawing, forming part thereof.

Figure 1 is a front perspective view of a grinding machine showing our new design; and
Figure 2 is a rear perspective view thereof.

We claim:

The ornamental design for a grinding machine, substantially as shown.

MILBURN A. HOLLENGREEN,
HAROLD E. BALSIGER.
